UNITED STATES PATENT OFFICE

2,444,242

MAGNETRON

John P. Blewett, Scotia, N. Y., assignor to General Electric Company, a corporation of New York

Application May 9, 1942, Serial No. 442,345

5 Claims. (Cl. 250—27.5)

1

The present invention relates to improvements in high frequency electronic devices of the magnetron type.

A known type of magnetron employs a cylindrical array of mutually spaced anodes grouped about a centrally located emissive filament or cathode. The emitted electrons are subjected to a magnetic field and their resultant gyrations about the cathode produce high frequency oscillatory voltages across the gaps separating the various anodes.

It is characteristic of magnetrons of this class that they tend to be somewhat unstable in operation. This is a result of the fact that at least certain of the electrons emitted from the cathode tend to return to the cathode with increased energy derived from the high frequency field which exists in the interelectrode space. The dissipation of this energy at the cathode surface raises the temperature of the cathode and increases its emissivity, this process being sometimes cumulative to such an extent that the cathode is destroyed. Even in cases where the cathode is not destroyed, the resultant variations in electron current cause an objectionable change in the properties of the magnetron as a whole.

It is an object of the present invention to provide a multianode magnetron device which is essentially free of the undesirable qualities described in the foregoing. In general, this is accomplished by the provision of a cathode structure of such form that the emissive component is exposed to insufficient bombardment materially to affect its emitting properties. As will be explained more fully at a later point, a particular cathode construction which serves this purpose has the further advantage of raising the operating efficiency of the magnetron as a whole.

The features of the invention desired to be protected herein are pointed out with particularity in the appended claims. The invention, itself, may best be understood by reference to the following description taken in connection with the drawings, in which Fig. 1 is a longitudinal section of a magnetron device suitably embodying the invention; Fig. 2 is a section taken on line 2—2 of Fig. 1; Fig. 3 is a fragmentary view illustrating in detail the construction of a portion of the cathode of Fig. 1; Fig. 4 is a schematic external view of the device of Fig. 1 and serves to illustrate the circuit connections for the device; Fig. 5 is a sectional view of a modified application of the invention; and Fig.

2

6 is a section in another plane of the device of Fig. 5.

Referring particularly to Fig. 1, there is shown a magnetron device which comprises an elongated cylindrical envelope 10 constituted of glass. This includes an anode structure comprising two semi-cylindrical metallic elements 12 and 13 which are arranged in opposed relation so as to provide a cylindrical array. As is shown most clearly in Fig. 2, elements 12 and 13 are mutually spaced to provide gaps 14 and 15 between them and are respectfully supported by conductors 16 and 17 which extend through the extremity of the envelope 10.

15 Within the anode structure there is provided a cathode assembly which in the first instance includes a pair of flanged, semi-cylindrical conductive (e. g. metallic) parts 18 and 19 which conform generally to the shape and disposition of the anode elements 12 and 13. The parts 18 and 19 are respectively supported by conductors 22 and 23 which extend through the lower extremity of the envelope 10.

25 The conductive cathode parts 18 and 19 are mutually spaced to provide gaps 25 and 26 between them and in these gaps there are located electron emissive filaments 28 and 29 arranged in parallelism with one another. The filaments are joined at one extremity by means of a conductive cross-bar 31 and at their opposite extremities are associated with lead-in conductors 34 and 35 sealed into a stem press 36 (Fig. 3). Tension is applied to each filament by means of coil springs 37, 38, respectively, connected between the filaments and their associated lead-in conductors. A center tap connection for the filament combination is provided by means of a conductor 40 which is joined to the cross-bar 31 and which is also sealed through the stem press 36.

30 The circuit connections of the various electrode elements so far referred to are indicated in Fig. 4. As appears in this figure, heating current is supplied to the filament conductors 34 and 35 by means of a battery 46 connected between them. The center point of the battery is connected to the conductor 40 and is also connected to the center of a short-circuiting bar 49 extending between the conductors 22 and 23. Potential is impressed between the cathode assembly and the anode structure comprising the elements 12 and 13 by means of a battery 58 which has its positive terminal connected to a 35 conductive cross bar 51 extending between the

externally projecting portions of the conductors 16 and 17. By this means a unidirectional electric field is established between the cathode assembly and the anode structure.

In the operation of the device a magnetic field is produced parallel to the various interelectrode gaps by means of a coil 55 which surrounds the envelope 10 in a region coextensive with the electrode system. This coil is energized by the application of a unidirectional potential.

As a result of the combined action of the magnetic field and the electrostatic field produced between the anode elements and the cathode assembly the electrons emitted by the heated filaments 28 and 29 move orbitally around the cathode assembly so as to form a rotating space charge in the interelectrode space. As a consequence of the electron gyrations, high frequency potentials are developed between the anode elements 12 and 13, that is, across the gaps which separate these elements.

The frequency of the oscillating voltage thus obtained may be controlled by proper adjustment of the circuit means interconnecting the anode elements. In the illustrated construction, this may be done by adjusting the location of the cross bar 51 (Fig. 4) to cause the conductors 16 and 17 to function as a quarter-wave transmission line shortened by the interelectrode capacity and resonant at the desired frequency of operation.

As a result of the adoption of a cathode construction of the type illustrated, only a minor proportion of the electrons emitted from the filaments 28 and 29 are able to return to these filaments, the greater number of the reversed electrons being intercepted by the semicylindrical parts 18 and 19. Due to the relatively extensive surface area of these parts and due further to the fact that they are not normally maintained at an emissive temperature, their bombardment does not affect the total electron supply and consequently does not produce any tendency for a runaway action to occur. On the contrary, even under relatively adverse operating conditions, these parts can still run well below an emitting temperature so that the cathode assembly as a whole may be regarded as an inherently stable system.

An improvement in the efficiency of the device as a whole can be realized by connecting the cathode parts 18 and 19 in such fashion that they are adapted to follow the oscillations of the anode elements 12 and 13. This may be accomplished for example, by locating the short-circuiting conductor 49 (Fig. 4) at such a place that the combined effect of the cathode and anode circuits is to produce resonance at the desired operating frequency. The two cathode parts are respectively sufficiently well coupled to the corresponding anode elements so that with this arrangement they will oscillate in phase with these elements. There will then be no high frequency field tending to accelerate electrons back to the cathode, and the conversion efficiency of the magnetron will be materially increased.

It will be understood that where very high frequencies are desired, more than two anode elements may be employed. In this event the number of cathode parts should be correspondingly increased.

A further application of the invention is illustrated in Fig. 5 which shows a magnetron of a type more fully described and claimed in my co-pending application, Serial No. 442,346, filed May

9, 1942, now Patent 2,428,612, issued October 7, 1947.

In this case the operating elements of the device are enclosed within a cylindrical metal container 60 and include a cathode assembly made up of an activated filament 61 and a flanged plate 62, the filament and plate being directly connected as indicated at 64 in Fig. 6. A collector 65 for the electrons emitted by the filament is provided at one end of the cathode assembly, being connected to an anode structure to be described in the following. A series of eyelet seals 66 are provided for the purpose of supplying potential to the various electrode elements enclosed by the container 60.

The anode structure is formed of a unitary rectangular block 68 of conductive metal such as copper and is provided at the edge which faces the cathode assembly with a series of mutually displaced slots 70 to 73. These serve the double function of dividing the structure into a series of independent anode elements and of providing space resonant cavities between adjacent elements. These cavities, which are defined by the opposed metallic surfaces of the anode elements, may be regarded as quarter wave resonant transmission line sections having voltage loops at their respective openings. Accordingly, if appropriate excitation is assumed, high frequency alternating voltages may be developed between the adjacent anode elements. The various resonant systems thus provided are inherently coupled to one another so that their action is mutually reinforced.

In order to obtain resonance effects of the desired character electrons are supplied to the space between the cathode plate 62 and the anode structure by the emissive filament 61 which lies in a semi-cylindrical depression provided near one extremity of the plate 62. A unidirectional potential is impressed between the cathode and anode structures from an external source (not shown) and a magnetic field parallel to the gaps 70 to 73 is provided by an external magnet having poles 75 and 76 (Fig. 6).

As is explained in my aforesaid prior application, Serial No. 442,346, the construction of Fig. 5 simulates the action of a fragmentary segment taken from a cylindrical multi-anode magnetron of infinite diameter. That is to say, the gyrations of the electrons emitted from the filament 61 as they pass in proximity to the various anode elements excite the elements in the manner characteristic of magnetron operation. Insofar as the present invention is concerned the arrangement has the advantage attributed to the construction of Fig. 1 that the cathode is incapable of runaway operation, so that the functioning of the device as a whole is inherently stable.

In order to take power from the device of Fig. 5, use can be made of a coupling loop 78 which is terminally connected to the anode structure as indicated at 80 and which is brought out through the wall of the container 60 through a conductive tube (e. g. a transmission line) illustrated at 82. A glass bead 83 sealed into the tube preserves the vacuum within the container.

While the invention has been described by reference to particular embodiments it will be understood that numerous modifications may be made by those skilled in the art without departing from the invention. I therefore aim in the appended claims to cover all such equivalent

variations as come within the true spirit and scope of the foregoing disclosure.

What I claim as new and desire to secure by Letters Patent of the United States, is:

1. A magnetron device comprising an anode structure including a cylindrical array of mutually spaced anode elements defining parallel gaps between them, a cathode assembly within the anode structure and comprising a hollow cylindrical conductive structure having an extended surface facing said anode elements, said conductive structure being divided axially providing a gap parallel to the said interanode gaps, an electron emissive element in said gap, and magnetic means adjacent said structure for producing a magnetic field in the space between the said anode structure and the said cathode assembly and in a direction parallel to said gaps.

2. A magnetron device comprising an anode structure including an array of anode elements which are mutually spaced apart providing gaps between them, a cathode system adjacent to the said anode structure comprising a plurality of spaced conductive parts which correspond in number and arrangement to the said anode elements, means included in said cathode system for supplying electrons to the space between said anode elements and said conductive parts, means resonant at a desired operating frequency interconnecting the anode elements, and means interconnecting the said conductive parts and resonant at said frequency.

3. A magnetron device comprising an anode structure including an array of anode elements which are mutually spaced providing gaps between them, a conductive structure having a surface opposed to said anode structure and conforming approximately to the shape of said array, said conductive structure being divided into spaced parts which correspond in number and configuration to said anode elements, an electron emitter exposed to only a portion of the anode structure for supplying electrons to the space between said anode elements and said conductive parts, said emitter being adapted to be maintained at the same direct current potential as said conductive structure during operation of the device, means interconnecting the said anode elements, and further means interconnecting the said conductive parts, both said interconnecting means being resonant at a desired operating frequency.

4. An electron discharge device of the magnetron type comprising spaced anode elements defining a plurality of mutually parallel gaps therebetween, a cathode assembly comprising a conductive structure opposed to said anode elements and having a surface substantially coextensive with the said elements, said structure having an opening parallel to and substantially coextensive with the longitudinal dimension of said gaps, and an elongated thermionically emissive

filament within said opening constituting an electron emissive source parallel to and coextensive with the longitudinal dimension of said gaps for supplying electrons to the space between said structure and said anode elements, said filament constituting a component of the said cathode assembly but providing only a minor fraction of the total area thereof, and magnetic means adjacent said structure to produce a magnetic field in the space between said anode elements and cathode assembly in a direction parallel to said gaps.

5. An electron discharge device of the magnetron type comprising an anode structure including a plurality of mutually spaced anode elements defining a plurality of mutually parallel gaps therebetween, a cathode assembly comprising a conductive structure opposed to said anode elements and having a surface substantially parallel to and coextensive with said anode elements, and an elongated thermionically emissive cathode element adjacent said member parallel to and substantially coextensive with the longitudinal dimension of said gaps for supplying electrons to the space between said conductive structure and said elements, said anode elements, said conductive structure and said cathode element being substantially coextensive in length and said cathode element being of small area compared to the area of said conductive structure whereby a substantial proportion of electrons returning from said anode elements to said cathode assembly may be intercepted by said conductive structure and thereby prevented from bombarding said cathode element, and magnetic means adjacent said structure to produce a magnetic field in the space between said anode elements and cathode assembly in a direction parallel to said gaps.
